UNITED STATES PATENT OFFICE.

ALBERT S. JANIN, OF NEW YORK, N. Y., ASSIGNOR OF ONE-THIRD TO WILLIAM J. COLE, OF NEW YORK, N. Y.

ELECTRIC TROLLEY.

No. 873,668.

Specification of Letters Patent.

Patented Dec. 10, 1907.

Application filed August 14, 1905. Serial No. 274,057.

To all whom it may concern:

Be it known that I, ALBERT S. JANIN, a citizen of the United States, and a resident of the city of New York, Clifton, borough of Richmond, in the county of Richmond and State of New York, have invented a new and Improved Electric Trolley, of which the following is a full, clear, and exact description.

This invention relates to trolleys, and it 10 consists substantially in the details of construction and combinations of parts herein-after more particularly described and pointed out in the claims.

The invention has reference more especially to trolleys for overhead electric railway systems, though equally applicable to under-ground systems, and one of the principal objects of the invention is to provide a device of this kind of an embodiment overcoming 20 numérous disadvantages and objections encountered in the use of many other contrivances hitherto devised for similar purposes.

A further object is to provide a device of the character mentioned which is simple in 25 construction and comparatively inexpensive to manufacture, besides being thoroughly effective and reliable in operation, and possessing the capacity for long and repeated service.

30 The above and additional objects are attained by means substantially such as are illustrated in the accompanying drawings forming a part of this specification, in which similar characters of reference indicate corresponding parts in all the views, and in whieh

Figure 1 is a view in perspective showing my improved trolley device as mounted upon the top portion of a car in operative relation with an overhead conductor for supplying 40 electric current thereto; Fig. 2 is an enlarged part sectional view in detail, of the rotatable contact-member of the trolley; and Fig. 3 is an enlarged sectional side view showing more clearly the construction and organization of 45 the parts comprising my improved trolley.

Before proceeding with a more detailed description, it may be stated that in the form of my improvements herein shown, I employ a metallic structure comprising a special base 50 by which to secure the structure to the top of the car, and disposed upon which, at opposite sides thereof, are duplicate sets of spindles or other means upon which are ro-

tatably mounted the lower ends of the lower members of duplicate sets of specially constructed upwardly disposed toggle-levers, the upper members of which are articulated with said lower members, and also with each other at their upper ends, at which ends said upper members of the sets of said levers are provided with bearings or supports for the spindle of a specially constructed rotatable contact-member (trolley), which I employ for maintaining a constant electrical connection with the overhead conductor of the railway system, thus to supply the electric current to the motor on the car for propelling the latter. Special means are employed tending at all times to force the upper and lower members of the two sets of toggle levers together and upwardly, thereby to maintain effective contact of the contact-member (trolley) with the overhead conductor, the said lower ends of the said lower members of the two sets of toggle levers being suitably connected together for effective operation of the structure, as will presently be explained.

The construction and organization of the parts of my improved device are such that the wear of said parts, as well as that produced upon the electric conductor of the railway system, is reduced to a minimum, thus obviating frequent changes or substitutes for the contact-member (trolley). Moreover, the contact-member (trolley) which I employ is not apt to leave the conductor at whatever speed the car may be moving, and whenever the car is switched from one track-section of the railway system to another or branch section, the said contact-member in virtue of the special construction thereof enables the conductor for the one section of railway to readily leave the contact-member at one of its ends, while the other end of said contact-member glides with equal facility beneath the conductor of the branch section, thus requiring practically no special handling or manipulation of the device on the part of the operator. Special means are employed, however, by which the contact-member may be lowered or otherwise manipulated by the operator on the car, through the medium of a rope or cable extending from the top of the car at one end. The contact-member or trolley proper is formed with special means whereby the same may be lubricated at the

bearing-positions thereof, and the entire embodiment of my improvements is such as to give the best results in practice.

Reference being had to the drawings by the designating characters thereon, 1 represents the top of an ordinary railway car 2, mounted upon which is a metal base 3 of any desired form or shape, but shown herein as rectangular. Said base is secured to the upper surface of the top of the car by means of screws 4, or in any other suitable way, and adjacent to the opposite side-edges 5 thereof are oppositely disposed bearings 6, in each of which are rigidly mounted duplicate screws 15 or spindles 7, on which in turn are rotatably mounted intermeshing pinions 8 and 9, which are rigid with the lower ends or extremities of sets of reversely disposed lower members 9 of toggle-levers 10, the sets of upper 20 reversely disposed members 11 of which cross or overlap each other at their upper ends, as indicated at 12, said ends being provided with corresponding openings (see Fig. 2) for the support of journals, such as indicated at 13, at the ends of a transversely disposed shaft or spindle 14, which is provided a suitable distance from the extremities thereof with oppositely disposed cones, such as indicated at 15, co-operatively associated 25 with which are the heads 16 of an elongated hollow cylinder 17, said heads being reduced at their inner extremities as indicated at 18, thus to form collars to which the ends of the cylinder 17 are fitted flushly, and secured to 30 the heads in any suitable manner, as by means of screws indicated at 19. The said cylinder 17 is of metal, as are all the other parts of my improved structure, and it will be observed that each of the said heads 16 is 35 substantially of semi-spherical contour, the purpose of which construction will be presently explained.

Each head 16 of the cylinder is provided with a central opening 19^a therethrough for 40 enabling the cylinder to be rotated about the shaft, and this opening merges into an outwardly enlarged recess 20, the walls of which are disposed about and a suitable distance from the surfaces of the hereinbefore-mentioned cone 15, thus to provide a race for the accommodation of anti-friction balls 21, see more especially the enlarged detail, Fig. 2. The outer end or base of the cone is separated from the inner one of the adjacent upper 45 crossed ends of one set of the upper members 11 of the toggle-levers referred to, while each journal 13 of the shaft 14 may also be provided with an outer washer 13^a, the severally-recited parts being held in proper assemblage by means of a nut 23, it being apparent that in the operation of the trolley the cylinder 17 is free to rotate upon the ball-bearings thus provided therefor within the heads 16 at the ends thereof. By the 50 introduction of any suitable lubricant within

the recess 20 it is apparent that the bearings for the cylinder may be rendered smooth and easy running, as well as practically noiseless, without any tendency to binding between the parts.

The upper extremities of each of the sets of lower members 9 of the toggle-levers 10 are preferably provided with outwardly extending bearings 24, in which are supported transverse connecting-rods 25 between said members, while the lower extremities of the upper members 11 of each set thereof are similarly provided with bearings 26 mounted on the said connecting-rods 25, within and adjacent to the bearings 24, it being noted 55 that the lower members 9 of each set thereof are joined or united by means of a horizontal brace 27, as well as diagonally disposed braces 28, secured thereto at 29 and also to the inner sides of the said members 9 at 30. 60 The members 11 of each set thereof are similarly connected near their upper ends by means of a horizontally disposed brace 31 and inclined or divergent braces 32 joined to the under side of the said brace 31 at 33 and 65 to the inner sides of the said members 11 at 34.

The base 3 hereinbefore referred to is provided inwardly of each of the bearings 6 thereon, with parallel plates 35, connected together in any suitable way, as by means of pins 36, as shown, the said pins being located on either side of and beyond the hereinbefore-mentioned spindles 7. Oppositely disposed to each other on either side of the 70 hereinbefore-mentioned horizontal braces 27, between the members 9 of both sets, are duplicate coiled springs 37, the inward terminals of which, on either side of substantially the longitudinal center of the base 3, 75 extend upwardly to a suitable height in the form of an arch, the sides of which are indicated at 38, and the connecting member of which is indicated at 39, while the outer extremities of these springs extend along the 80 base 3, as indicated at 40 for instance, and have the terminals 41 thereof turned inwardly substantially at right angles, the ends of said terminals being formed into eyes or loops 42 secured to the base by means 85 of screws 43 passing through the eyes and entering the base. The normal position of the arches of the springs of the two sets is practically vertical, said arches being on either side of the horizontal connecting 90 members 27 of the lower parallel members 9 of the toggle-levers, and it will be seen that from the powerful tension upon these arches, the sets of members 9 and 11 of the toggle-levers are given a tendency at all times to 95 distend or straighten out vertically. In this way, it is apparent that the cylinder 17 will be held beneath the supply conductor 44 of the railway system in such manner as to 100 always be in perfect electrical contact with 105

said conductor, and in virtue of the special form of the ends of the cylinder, it will be seen that whenever the same may be carried from beneath the conductor over one line or section 5 of railway to be switched onto another line or section, the cylinder 17 will readily find its way to operative position beneath the conductor of the second or branch line, practically without requiring any special manipulation there- 10 of on the part of the operator. It will be seen that the said cylinder 17 is of considerable length comparatively, thus to insure the same not leaving the under side of the conductor 44 during the travels of the car, and 15 that although the spring devices herein described tend at all times to carry the lower and upper members of the toggle-levers together, in distension vertically, for the purposes already explained, they still yield sufficiently under any necessary force brought 20 to bear thereon, to permit the cylinder 17 to be lowered in conformity with any cause tending to produce such lowering thereof.

In order to enable my improved trolley 25 device to be manipulated or operated at any time from a platform of the car, I provide a rope or cable 45, having at the upper end thereof suitable branches 46 which are secured at 47 in any suitable way to the horizontal braces 31 for the upper members 11 of the toggle-levers, the said rope or cable being carried around a pulley 48 suitably mounted in bearings 49 therefor secured to the upper side of the base 3, thence carried 30 toward one end or the other of the car, as indicated at 50, whence it may be allowed to hang over in such manner as to be conveniently taken hold of by an operator on the

platform of the car, to cause the cylinder 17 to be lowered by exerting sufficient pulling 40 force upon the said cord or cable.

In the general statement hereinbefore given of the parts constituting my improvements I have employed the term "contact-member" interchangeably with that of 45 "trolley," it being understood that the element intended thereby is the cylinder 17.

Having thus described my invention, I claim as new and desire to secure by Letters Patent:

A trolley for electric railways, comprising a base, an adjustable double diamond-shaped frame movably mounted on said base, said frame construction including reversibly disposed sets of upper and lower members, the 55 upper members of each set being united by a brace, a pulley mounted on the base, a cable connected to each brace and passing beneath the pulley, the upper members of the frame being provided at their upper ends with a rotatable device for electrical contact with the conductor of the system, embodying a rotatable cylinder having removable heads of semi-spherical form, the latter having openings and concaved recesses therein, a shaft 60 65 extending through said openings and provided with a cone entering each of said recesses, and rolling objects between the sides of each recess and cone.

In testimony whereof I have signed my 70 name to this specification in the presence of two subscribing witnesses.

ALBERT S. JANIN.
